UNITED STATES PATENT OFFICE

2,517,683

BOWLING ALLEY SIGNAL SWITCH

Charles T. Kovac, Youngstown, Ohio

Application May 15, 1947, Serial No. 748,199

1 Claim. (Cl. 200—52)

1

This invention relates to bowling alleys and more particularly to signal systems therefor.

The principal object of the invention is the provision of a signal system for a bowling alley.

A further object of the invention is the provision of a switch device for positioning in a bowling alley.

A still further object of the invention is the provision of a signal system for a bowling alley actuated by weight of the bowling pins.

A still further object of the invention is the provision of a signal system for a bowling alley which may be used in connection with the automatic pin setting installations and in no way affects the formation or construction of the bowling pins employed.

A still further object of the invention is the provision of a switch member for installation in a bowling alley signal system, the switch being operable by weight and movable approximately one-thousandth of an inch so as to maintain the flush, smooth surface of the bowling alley.

The bowling alley signal system shown and described herein has been devised for installation in bowling alleys to enable a ready determination of the pins standing and their locations to be made. It is well known in the art that various types of circuit closing devices have been proposed for installation in bowling alleys and these have uniformly required the presence of a metal conductor on the bottom of the bowling pin to be operative. Such devices are objectionable in that it is necessary to add a metallic member to each of the bowling pins and the rules of the governing authorities do not permit such additions or alterations in bowling pins if the scores are to be recognized as official.

The present invention relates to a bowling alley signal system which is operative by the weight of the bowling pins alone and thereby capable of use with any bowling pin so as to make possible tournament and official score play on a bowling alley equipped with the signal system herein disclosed.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

2

Figure 1 is a perspective view of a portion of a bowling alley and a signaling board positioned adjacent thereto.

Figure 2 is an enlarged vertical cross section taken on line 2—2 of Figure 1 and illustrates a portion of a bowling pin and a switch member positioned in the bowling alley.

Figure 3 is a wiring diagram of the bowling alley signal system.

10 Figure 4 is a horizontal cross section taken on line 4—4 of Figure 2.

Figure 5 is a horizontal cross section taken on line 5—5 of Figure 2.

15 Figure 6 is a side elevation of the switch member shown in Figures 2, 4 and 5.

By referring to the drawings and Figure 1 in particular it will be seen that a bowling alley 10 is provided with a plurality of switch members 11 arranged in the pattern in which the bowling pins used in the alley are positioned for play. One of the bowling pins is illustrated in position in one of the switch members 11 and is indicated by the numeral 12. Adjacent the bowling alley there is a signal board 13 and a plurality of signal lights 14 are positioned therein in the same pattern as the switch members 11 in the bowling alley 10. Electrical circuits are employed to connect the switch members 11 and a suitable power source with the signal lights 14, and by referring to Figure 3 of the drawings a symbolic wiring diagram may be seen.

In Figure 3 of the drawings the switch members 11 are illustrated in operative connection with terminal blocks 15 and 16 by means of circuit wires 17, the terminal blocks 15 and 16 being in operative electrical connection with the signal lights 14 by means of a plurality of electric conductors 18.

40 A power source comprising a transformer 19 is disclosed, it being obvious that electric currents of very low voltage are preferred so that there will be no danger of arcing or shock in the installation.

By referring now to Figure 2 of the drawings 45 it will be seen that a detailed view on an enlarged scale illustrates a portion of the bowling pin 12 in position on one of the switch members 11 which in turn is disposed in an opening 19 in the bowling alley 10. The switch member 11 includes a visible top portion 11, as shown in the several figures of the drawings, and a base section 20 disposed therebeneath. The base section 20 has an upstanding annular rim 21 thereabout and a ring 22 disposed immediately adjacent the upstanding rim 21 and affixed to the base 20 by means of a plurality of screws 23. A spring

member 24 is positioned centrally in the area defined by the ring 22 and has a plurality of radially spaced arms 25 which are elevated with respect to the upper surface of the base 20.

The top portion 11 of the switch member has a metal disc 26 positioned therein which is normally supported in elevated relation to the metal ring 22 by means of the radially spaced arms 25 of the spring 24.

In order that the assembly may be held together to form the complete switch member 11, a plurality of screws 27 are positioned upwardly through the base 20 which is countersunk to provide for the reception of the heads of the screws 27 so that the screws 27 engage threaded openings 28 in the disc 26 which in turn is affixed to the top portion 11 by means of a plurality of screws 29.

In order that an electrical circuit may be established between the disc 26 and the ring 22 when they are engaged by reason of the compression of the spring 24 and the downward movement of the arms 25 thereof as by the weight of a bowling pin 12 positioned on the top portion 11 of the switch member, circuit wires 17 establish connection with the ring 22 and the spring 24 as illustrated in Figure 3 of the drawings.

It will be seen that the screws 27 provide for the adjustment of the device by enabling the base 20 and the top portion 11 to be moved into very close relationship, for example, one thousandth of an inch or more. This is a sufficient clearance between the contact portions of the switch member which comprise the ring 22 and the metal disc 26. The slight spacings of the ring 22 and the disc 26 eliminate any tilting of the top portion of the switch member 11 so that the bowling pin 12 positioned thereon, in order to close the circuit therethrough, is not tilted or affected in any way. The switch member is provided with a central opening 31 to accommodate portions of an automatic pin setting machine such as commonly employed in bowling alley constructions.

It will thus be seen that the several objects of the invention are met by the bowling alley signal system shown and described herein and particularly the switch members 11 incorporated in the bowling alley and by means of which the signal board 13 is controlled. The switch mem-

bers 11 as well as the other portions of the signal system for bowling alleys disclosed herein may be economically formed and simply and efficiently installed in existing bowling alleys. It will be obvious that the provision of the signal system considerably expedites play in the bowling alley as the standing pins are clearly marked by the signal board which serves as an efficient and accurate guide to the player at all times.

Having thus described my invention, what I claim is:

A switch member for installation in a bowling alley including an insulating base and an insulating top portion, a metallic disc secured beneath said top portion and a metallic ring positioned on said base portion in oppositely disposed relation to said metallic disc, said disc and ring comprising electrical contact members, a spring member comprising a ring having a plurality of radially spaced, upwardly extending arms thereon positioned on said base portion and within the area of the said metallic ring thereon, the said radially spaced arms of the said spring member engaging the said metallic disc and holding the same and the said top portion in spaced relation to the said metallic ring on the said base portion, means securing the said top and base portions in proximity to one another and conductors establishing electrical connection with the said spring member and metallic ring whereby an electrical circuit may be closed through the switch member upon the top portion being moved downwardly to bring the said metallic disc and metallic rings into contact with one another.

CHARLES T. KOVAC.
